(57) **CLAIM**

The ornamental design for a tip assembly for a cryogenic device, as shown and described.

DESCRIPTION

FIG. 1 is a top isometric view of a tip assembly for a cryogenic device.

FIG. 2 is a bottom isometric view of the assembly of FIG. 1.

FIG. 3 is a front view of the assembly of 1.

FIG. 4 is a back view of the assembly of 1.

FIG. 5 is a left side view of the assembly of 1.

FIG. 6 is a right side view of the assembly of 1.

FIG. 7 is a top view of the assembly of 1; and,

FIG. 8 is a bottom view of the assembly of 1.

The broken lines in the drawings illustrate portions of the tip assembly for a cryogenic device that form no part of the claimed design.

1 Claim, 8 Drawing Sheets
